UNITED STATES PATENT OFFICE.

ADOLF A. SEE, OF LAKE CHARLES, LOUISIANA.

DESIGN FOR A CHAIR OR SIMILAR ARTICLE OF FURNITURE.

Application filed December 3, 1927. Serial No. 24,370. Term of patent 14 years.

To all whom it may concern:

Be it known that I, ADOLF A. SEE, a citizen of the United States, residing at Lake Charles, in the parish of Calcasieu and State of Louisiana, have invented a new, original, and ornamental Design for Chair or Similar Article of Furniture, of which the following is a specification, reference being had to the accompanying drawings, forming part thereof.

I claim:

The ornamental design for a chair or similar article of furniture as shown.

ADOLF A. SEE.
